UNITED STATES PATENT OFFICE.

WILLIAM GARRETT GRAY, OF EDDYVILLE, KENTUCKY.

TOBACCO-PIPE BUTTON.

1,097,713.

Specification of Letters Patent.

Patented May 26, 1914.

Application filed May 29, 1913. Serial No. 770,640.

To all whom it may concern:

Be it known that I, WILLIAM GARRETT GRAY, citizen of the United States, residing at Eddyville, in the county of Lyon and

5 State of Kentucky, have invented certain new and useful Improvements in Tobacco-Pipe Buttons, of which the following is a specification.

This invention relates to an improved tobacco pipe, and the primary object thereof is to provide an attachment which will effectively exclude the nicotin and moisture precipitated within the bowl, from the

10 smoker's mouth.

15 A further object of the invention contemplates the provision of a simple, cheap and efficient pipe attachment in the nature of a removable button which will retain the nicotin and prevent its passing on into the mouth of the smoker, will act as a smoke circulating chamber or reservoir within which the smoke is temporarily strained and allowed to cool, will prevent particles of tobacco from clogging the stem, and which

20 will itself be non-poisonous, odorless, tasteless and non-combustible, and one which may be removed, cleaned and used repeatedly if desired.

The invention still further resides in the provision of a pipe button which may be removed at will, readily cleaned and quickly applied to pipes of various sizes, shapes and kinds.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:—

Figure 1 is an elevation of an ordinary pipe; Fig. 2 is a longitudinal sectional view of the pipe bowl, with the attachment arranged therein, the pipe stem being partly broken away; and Fig. 3 is a top plan view of the pipe button, partly broken away.

Before proceeding with the description of the drawings, I desire to call particular attention to the fact that while I have evolved my invention and have illustrated the same

in connection with an ordinary straight stem corn cob pipe, the same may be readily utilized or employed in connection with any and all pipes of ordinary construction. 60

Referring now to the drawings, the numeral 1 designates the bowl and 2 the stem the latter extending through the bowl as at 3 in spaced relation to the base thereof in the ordinary manner.

Absorbent material 4 of any suitable composition is arranged or disposed within the bowl 1, the stem 2 projecting thereinto so as to force or cause the smoke when drawn through the stem to pass through the said material, the latter absorbing the moisture usually precipitated within the bowl and preventing the same from entering the smoker's mouth. Arranged over the absorbent material 4 is disposed a hollow convexo-convex button, designated in its entirety by the numeral 5, the upper convexed surface of which is provided with a centrally disposed opening 6 through which the smoke from the lighted tobacco is drawn into the chamber or reservoir formed by the hollow of the button. Other openings 7 are formed within the lower convexed surface of the button in spaced relation or out of alignment with the opening 6, the said openings 7 being preferably disposed near the edge or periphery of the button so as to produce a seat adapted to collect and strain the nicotin of the smoke as it is circulated or drawn through the chamber formed by the said button. By disposing the openings 7 near the sides of the button 5 it will be seen that the smoke is forced, when drawn through the opening 6, against the inner concaved face of the button base where it is deflected toward the inner periphery of the button and out through the openings 7 formed therein, the nicotin being retained within the reservoir or chamber while the smoke passes into the absorbent material 4 and out through the stem 2 in a purified condition. 90

The provision of the chamber or reservoir disposed as it is above the absorbent material 4 allows the smoke to circulate and become cooled before entering the said material, and conditions the same before reaching the mouth of the smoker so as to allow him to enjoy a cool, sweet smoke. The button being removable, the same may be easily withdrawn from the bowl and cleaned in any suitable manner and then replaced for further use without in any way affecting the 105

110

utility thereof. The openings 6 and 7 being disaligned will prevent particles of tobacco from being drawn into the stem 2, the absorbent material 4 acting as a check for 5 the said particles should the same be drawn through the openings 7.

It will be seen from the above, taken in connection with the accompanying drawings that the button being composed of non-
10 poisonous and non-combustible material the same may be used indefinitely and applied or employed in connection with pipes of various character; that the said button being of odorless and tasteless material, the pleasure derived from the smoking of the pipe is in no way rendered less enjoyable; and that if desired a button slightly smaller than the inner periphery or wall of the bowl may be applied so as to create a draft equally upon
15 20 all sides of the tobacco and through the center and cause the same to burn until entirely consumed.

It will be understood that the above description and accompanying drawings comprehend only the general and preferred embodiment of my invention and that various minor changes in the details of construction, proportion and arrangement of parts may be made within the scope of the
25 30 appended claims and without sacrificing any of the advantages of my invention.

Having thus fully described my invention, what I claim as new and desire to secure by Letters Patent, is:—
35 1. As a new article of manufacture, a one piece hollow convexo-convex button for tobacco pipes, the top of said button having a central opening formed therein, the bottom of said button having a plurality of
40 45 openings formed therein out of alignment with said top opening and adjacent the button periphery, that portion of the convex

bottom between the openings, forming a receptacle within which nicotin and moisture is strained, the arrangement of the top 45 opening causing the smoke to be deflected and circulated within the hollow button prior to its passage out through said bottom openings, as and for the purpose set forth.

2. In a tobacco pipe, the combination with a bowl, a stem in communication therewith, and absorbent material arranged within the bowl into which the said stem extends, of a hollow convexo-convex metallic button 55 adapted to be arranged over the said material and within the said bowl, the said button having openings formed in the top thereof, said button being further provided with openings in the bottom thereof through 60 which the smoke is drawn prior to its passage through the said material and out through the stem.

3. In a tobacco pipe, the combination with a bowl, a stem extending thereinto in spaced 65 relation to the bottom of the bowl, and absorbent material arranged within the bowl into which the said stem extends, of a hollow one piece convexo-convex metallic button arranged within said bowl over said material, the said button having an opening 70 formed centrally within the top thereof, and a plurality of openings formed out of alignment with said central opening in the bottom thereof, the hollow of said button forming a reservoir into which the smoke is drawn and circulated prior to its passage through the material and into the stem.

In testimony whereof I affix my signature in presence of two witnesses.

WILLIAM GARRETT GRAY.
